United States Patent Office

Des. 228,059

Patented Aug. 7, 1973

228,059

LITTER BOX

Cecil B. Woofter, Newton, Iowa, assignor to
The Vernon Company

Filed Aug. 31, 1971, Ser. No. 176,794

Term of patent 14 years

Int. Cl. D7—06

U.S. Cl. D7—193

FIG. 1.

FIG. 2.

FIG. 3.

FIG. 4.

FIG. 5.

FIG. 6.

FIG. 7.

FIG. 1 is a perspective view of a litter box embodying my new design;

FIG. 2 is a top plan view thereof;

FIG. 3 is a front elevational view;

FIG. 4 is a left side elevational view;

FIG. 5 is a right side elevational view;

FIG. 6 is a bottom plan view of the litter box; and

FIG. 7 is a rear perspective view.

I claim:

The ornamental design for a litter box, substantially as shown.
